(57) **CLAIM**

The ornamental design for a coupling member for a wearable physiological monitor, as shown and described.

DESCRIPTION

FIG. 1 is a top perspective view of a design for a coupling member for a wearable physiological monitor;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view, shown in an environment; and, FIG. 9 is another perspective view, shown in an environment.

In FIGS. 8 and 9, the broken lines illustrate environment only, that form no part of the claimed design.

1 Claim, 5 Drawing Sheets

US D1,114,268 S
